(57) **CLAIM**

The ornamental design for a sandal as shown and described.

DESCRIPTION

FIG. 1 is front right perspective view of a sandal showing our new design;

FIG. 2 is front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The broken lines shown in the figures are included for the purpose of illustrating environmental structure of the sandal and form no part of the claimed design.
